(57) **CLAIM**

The ornamental design for a multi-purpose clip, as shown, and described.

DESCRIPTION

FIG. 1 is a perspective view of a multi-purpose clip, showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines shown in the figures are for the purpose of illustrating portions of the multi-purpose clip and form no part of the claimed design.
